COUNTING DEVICES FOR USE WITH KNITTING NEEDLES

Norman Thomas Sanders, Mappleborough Green, Studley, England, assignor to Needle Industries Limited, Birmingham, England, a British company

Application January 21, 1958, Serial No. 710,331

3 Claims. (Cl. 116—133)

This invention relates to a counting device for use in association with a knitting needle, said device being of the kind comprising an inner sleeve or like assembly for threading on to the shank of the knitting needle and including individually rotatable co-axially assembled sleeve parts which, in combination with an outer sleeve, enable one or a group of numerals selected from a circumferentially spaced set marked on the inner sleeve or like assembly to be displayed.

One object of the present invention is to provide a new or improved construction.

A further object of the present invention is to provide a counting device wherein the individually rotatable co-axially assembled sleeve parts of the inner sleeve assembly are located with respect to each other in a simple and effective manner which allows of said parts of the inner sleeve assembly being rotatable with respect to each other and to the outer sleeve member.

Yet a further object of the present invention is to provide a counting device of the abovementioned kind wherein the parts of the inner sleeve assembly are axially located with respect to each other in a simple and effective manner.

It is also an object of the present invention to provide a method of making a counting device of the abovementioned kind, which method is particularly simple to perform and which enables the parts of the inner sleeve assembly to be formed in thermoplastic synthetic resin material.

In accordance with the present invention I provide in a counting device for use in association with a knitting needle and comprising an outer sleeve having a viewing aperture, and an inner sleeve assembly including relatively rotatable first and second sleeve parts bearing circumferentially spaced numerals on their outer surface and having respective end caps disposed on respective ends of said outer sleeve and projecting radially outwardly of said outer sleeve; means for retaining said sleeve parts against axial withdrawal from said outer sleeve, comprising a tubular portion of thermoplastic synthetic resin connected at one of its ends with said second sleeve part against axial movement relatively thereto and extending interiorly through said first sleeve part, said tubular portion having an integral laterally outwardly extending flange at the other of its ends, said first sleeve part being rotatably retained on said tubular portion between said second sleeve part and said flange.

The invention will appear more clearly from the following detailed description when taken in connection with the accompanying drawings, showing by way of example a preferred embodiment of the inventive idea.

The invention is illustrated in the accompanying drawings wherein:

Figure 1 is a view in diametral cross section of one construction of counting device constructed in accordance with the present invention, one of the inner sleeve parts being in the form which it occupies before displacement of material to retain it in assembled relationship

2

with the other sleeve part and the device being shown in aligned relation with a tool for use in effecting such material displacement.

Figure 2 is a further view of the same construction partly in diametral cross section illustrating the device after assembly on the tool, the latter having been brought into contact with a heating surface for heating and displacing the material of one of the sleeve parts, and

Figure 3 is a perspective view of a needle-like tool utilised in the manufacture of the counting device in the manner illustrated in Figure 2.

The general construction and arrangement of the parts of the counting device, particularly the means for retaining the outer sleeve thereof in any of a plurality of stopping positions and the means for retaining the device in use on the shank of a knitting needle form the subject of my co-pending U.S. patent applications Nos. 710,265 and 710,330, now Patent Nos. 2,887,858 and 2,872,892 respectively to which reference may be had for further details.

For convenience, however, it is herein stated that the device comprises an outer sleeve 10 formed of resilient strip material and of ten sided regular polygonal form, of which one side incorporates a gap constituting a viewing aperture. The inner sleeve comprises two main parts 11 and 12 incorporating drum elements 13 and 14 respectively, marked externally with circumferentially spaced numerals and rotatable relatively to each other and to the outer sleeve 10 so that any pair of numerals, one from each drum element, can be viewed through the aperture of the outer sleeve.

The parts 11 and 12 include end cap portions incorporating annular channels 15 and 16 in which the adjacent end portions of the outer sleeve 10 are received, and the outer side walls of these channels 15 and 16 are constituted by rings 17 and 18, each formed integrally with the respective end cap portion, and such rings 17 and 18 being also of regular ten sided polygonal form so as to establish the requisite stopping positions with respect to the outer sleeve 10, which is maintained in pressure contact with these rings by virtue of its own resilience.

Referring now specifically to the sleeve parts 11 and 12, one of these, namely, the part 11, incorporates a tubular portion 8, which is an integral extension of its drum element 13, the latter being secured by adhesive or in any other suitable manner in an annular groove 19 formed in the end cap portion of the sleeve part 11 outwardly of a further portion 20 of the same internal and external diameter as the portion 8.

The drum element 14 of the sleeve part 12 is assembled on the portion 8 so as to be rotatable thereon and said portion 8 is initially of a sufficient axial length to project beyond the end of the end cap portion of the sleeve part 12, as may be seen in Figure 1.

The end face of the sleeve part 12 incorporates an annular seating 21, constituted by an abutment face 22 lying in a plane radial to the axis of the bore 23 afforded by the portions 8 and 20 and a peripherally extending face 24 concentric with the portion 8.

At least the portion 8, and preferably all the components hereinbefore referred to, with the exception of the outer sleeve 10, are made of thermoplastic material. The sleeve part 12 is prevented from axial withdrawal from the portion 8 by displacing part of the material of the portion bordering on its end face so as to form a laterally outwardly projecting flange, part of which engages in the annular seating 21.

The sleeve part 12 is located against axial displacement on the portion 8 in an opposite direction by a shoulder 25 afforded by the sleeve part 11 at the junction of the portion 8 with the drum element 13.

For effecting displacement of the material as hereinbefore mentioned, it is preferred to employ a tool comprising a mandrel 26 of circular form in cross section and of a diameter which is a close sliding fit within the bore 23, the leading end portion 27 of this mandrel conveniently being tapered to facilitate entry into the bore or, as will be most usual in practice, to facilitate threading of the assembled parts of the counting device over the mandrel. At its lower end the mandrel is connected to a heat transmitting plate 28 so as to be in thermally conductive relationship therewith.

After assembling the counting device on the mandrel 26, as seen particularly in Figure 2, the plate 28 is heated at its underface, preferably by bringing it into contact with the surface 29 of a hot plate 30 whereby heat is rapidly transmitted through the plate 28 to the end face of the portion 8. Material bordering on this end face thus becomes softened, and simultaneously axial pressure is applied to the counting device in a direction towards the surface 29 so as to cause part of this material to spread laterally outwardly and form an integral flange 31. The extent of the spread is at least partly controlled by the existence of the peripheral face 24 of the seating 21 whilst the mandrel 26 prevents any inward spread so that in the region of the flange 31 the portion 8 is entirely free from any inward projections at all.

The mandrel 26 may be made as a solid rod, for example, from mild steel and the plate 28 may also be made of mild steel formed integrally with the mandrel but said plate is of thin configuration (typically having a thickness of 0.010 inch) so that the thermal capacity of the mandrel is appreciably greater than that of the plate. In this way, during the heating of the plate 28 the mandrel still remains cool and serves to prevent material bordering on the inner circumferential face from becoming heated and softened.

After the flange 31 has been formed, the tool is removed from contact with the surface 29 and the plate 28 is then cooled rapidly by reason of heat flowing from the plate to the mandrel 26. This avoids any excessive delay to allow for cooling of the flange 31 before removal of the counting device from the tool and thus appreciably reduces the production time required for each counting device.

Instead of forming the flange 31, the seating 21 may be so shaped as to form a rim or bead of part-circular or other section, or, alternatively, one or more laterally projecting lugs or castellations constituting retaining elements might be formed instead of a continuous flange by initially making the projecting end portion of the portion 8 of castellated form.

The means for retaining the counting device on the shank of a knitting needle when in use comprise coil springs such as that seen at 32, extending across the bore 23, the ends of such springs being retained in an annular recess 33 between the portions 8 and 20, as described in my co-pending U.S. patent applications above referred to.

What I claim then is:

1. In a counting device for use in association with a knitting needle, and comprising an outer sleeve having a viewing aperture, and an inner sleeve assembly including relatively rotatable first and second sleeve parts bearing circumferentially spaced numerals on their outer sur-

faces and having respective end caps disposed at respective ends of said outer sleeve and projecting radially outwardly of said outer sleeve; the provision of means for retaining said sleeve parts against axial withdrawal from said outer sleeve, comprising a tubular portion of thermoplastic synthetic resin connected at one of its ends with said second sleeve part against axial movement relatively thereto and extending interiorly through said first sleeve part, said tubular portion having an integral laterally outwardly extending flange at the other of its ends, said first sleeve part being rotatably retained on said tubular portion between said second sleeve part and said flange.

2. In a counting device for use in association with a knitting needle, and comprising an outer sleeve having a viewing aperture, and an inner sleeve assembly including relatively rotatable first and second sleeve parts bearing circumferentially spaced numerals on their outer surfaces and having respective end caps disposed at respective ends of said outer sleeve and projecting radially outwardly of said outer sleeve; the provision of means for retaining said sleeve parts against axial withdrawal from said outer sleeve, comprising a tubular portion of thermoplastic synthetic resin connected at one of its ends with said second sleeve part against axial movement relatively thereto and extending interiorly through said first sleeve part, said tubular portion having an integral laterally outwardly extending flange at the other of its ends, said first sleeve part being rotatably retained on said tubular portion between said second sleeve part and said flange and having at its end adjacent to said flange an axially directed abutment face and a radially inwardly directed butment face defining a seating into which said flange extends to engage with said abutment faces.

3. In a counting device for use in association with a knitting needle, and comprising an outer sleeve having a viewing aperture, and an inner sleeve assembly including relatively rotatable first and second sleeve parts bearing circumferentially spaced numerals on their outer surfaces and having respective end caps disposed at respective ends of said outer sleeve and projecting radially outwardly of said outer sleeve; the provision of means for retaining said sleeve parts against axial withdrawal from said outer sleeve, comprising a tubular portion of thermoplastic synthetic resin connected at one of its ends with said second sleeve part against axial movement relatively thereto and extending interiorly through said first sleeve part, said second sleeve part having an axially directed end face at its inner end disposed radially outwardly of said tubular portion to form a shoulder on said tubular portion at its inner end, said tubular portion having an integral laterally outwardly extending flange at the other of its ends, said first sleeve part being rotatably retained on said tubular portion between said shoulder and said flange and having at its end adjacent to said flange an axially directed abutment face and a radially inwardly directed butment face defining a seating into which said flange extends to engage with said abutment faces.
